US00D447196B1

(12) **United States Design Patent** (10) Patent No.: **US D447,196 S**
Bennett (45) Date of Patent: **** Aug. 28, 2001**

(54) **CURLING DEVICE**

517,103 * 3/1894 Hamilton 473/587
5,474,293 * 12/1995 Tanaka ..... 473/587 X

(75) Inventor: **John D Bennett**, Dymchurch (GB)

* cited by examiner

(73) Assignee: **Terence Michael Hart** (GB); a part
interest

(**) Term: **14 Years**

(21) Appl. No.: **29/130,273**

Primary Examiner—Dominic Simone
(74) Attorney, Agent, or Firm—Bachman & LaPointe, P.C.

(22) Filed: **Sep. 29, 2000**

(57) **CLAIM**

The ornamental design for the curling device, as shown and
as described.

(30) **Foreign Application Priority Data**

DESCRIPTION

Apr. 28, 2000 (GB) 2092517

FIG. 1 is a top plan view;

(51) LOC (7) Cl. **21-02**

FIG. 2 is an bottom plan view;

(52) U.S. Cl. **D21/710**

FIG. 3 is a front view; and,

(58) Field of Search D21/710; 473/587;
16/26

FIG. 4 is a side view.
